EDWARD HALL FAILE, OF NEW YORK, N. Y.

CONNECTOR FOR ELECTRIC CONDUCTORS.

1,188,054.

Specification of Letters Patent. Patented June 20, 1916.

Application filed September 16, 1914. Serial No. 862,026.

To all whom it may concern:

Be it known that I, EDWARD HALL FAILE, a citizen of the United States, and resident of the borough of Manhattan, city, county, and State of New York, have invented certain new and useful Improvements in Connectors for Electric Conductors, of which the following is a specification.

My invention relates to connectors commonly employed for securing the end of a multiple strand electric cable either to the end of another cable or to any suitable terminal, and relates more particularly to that type in which there is provided a socket having a portion of its internal wall of greater diameter than the cable inlet to the socket, so that the strands, after being inserted, may be wedged apart into the space of larger diameter.

20 The main essential feature of my invention involves the constructing of the socket with an extra recess or cavity, within which a body of solder or other fusible material is normally held or stored. In using my improved connector, it is not necessary to have any separate soldering apparatus as the solder within the socket may be melted by the application of heat to the exterior of the latter after the strands are spread apart.

25 The solder goes with the socket as a part of the same article of manufacture, so that when the cable is inserted in the socket and the strands are spread apart, it is only necessary to apply a torch or flame to the outer surface of the socket so as to melt the body of solder which is held within the latter. The solder, upon being melted, flows in among the strands and permanently holds the strands spread apart so that they cannot

30 be withdrawn from the sockets. The socket itself being of metal, not readily melted by the flame, will quickly conduct the heat directly to the solder.

It is evident that the details of construction of the connector may be varied without departing from the spirit of my invention and that, therefore, various different embodiments of my invention may be designed.

In the accompanying drawings, I have illustrated several different forms, each of which possesses certain advantages peculiar to itself, but all of which embody my broad invention.

In these drawings, Figures 1 to 4 inclusive show longitudinal sections through four different embodiments of my invention.

As previously pointed out, my invention involves the use of both a body of solder and a wedge in connection with a connector body or socket, the solder being incorporated within the socket prior to the insertion of the cable within the latter and prior to the spreading of the strands by the wedge. In the specific form illustrated in Fig. 1, I employ a metal socket 10 formed integral with an attaching lug 11. The attaching lug may be of any form or shape desired, depending upon the character of the structure to which the end of the cable is to be attached. The socket has an end wall 12 at the end bearing the lug 11 and has an internal chamber 13 of truncated conical form, the opened end being opposite to the end wall 12 and the chamber being of greater diameter adjacent to said end wall than it is at the entrance opening. The opening is made of such size as to receive the group of strands of the cable after the insulation of the latter has been removed for a distance slightly less than the depth of the chamber.

In one wall, preferably the end wall 12, there is provided a second and smaller opening, through which a wedge 14, preferably of conical form, may be driven. The body portion or outer end of the wedge is of substantially the size of the opening in the end wall, and the taper of the wedge bears such relationship to the taper of the peripheral wall of the chamber that when the wedge is driven into place, it spreads apart the strands of the cable, and the said strands lie in engagement with both the outer surface of the wedge and the inner surface of the socket.

Within the socket I provide a body of solder which is placed in position in any suitable manner prior to the insertion of either the cable end or the wedge. This solder is incorporated as a part of the same article of manufacture as the socket and is of such character that it may be readily melted by the application of heat to the outer surface of the socket.

In Fig. 1, I have illustrated the body of solder in the form of an annular ring 15 in engagement with the inner surface of the end wall 12 and encircling the opening in the latter. The solder ring may be of any desired thickness, although in practice it is only necessary to make it of sufficient thickness so that it will include enough solder to properly connect the wedge, socket and

strands together when the said solder is melted. By so placing the solder that the ends of the strands come adjacent to or into engagement with it, and by having it engage 5 circle the wedge, it is evident that the minimum flow of solder is required to effect a permanent holding of the strands in spread condition. It will be noted that in this specific form, after the strands and wedge 10 are inserted, there is no escape opening left for the solder, and that the latter may be melted with the socket in a vertical, horizontal or inclined position, depending upon the most convenient positioning of the cable.

15 Even though the solder should adhere only to the wedge and the strands, it is evident that this will positively prevent the strands from being pulled out, by reason of the fact that the entrance to the chamber is of smaller 20 diameter than the end of the cable after the latter has been expanded. If the solder adhere only to the strands and the socket, it will hold the ends of the cable in expanded position independently of the wedge and, 25 therefore, prevent the removal of the cable. If the solder adhere only to the socket and the wedge, it will prevent the removal of the latter and therefore prevent the contraction of the end of the cable; thus, even though 30 the solder be melted to an insufficient extent to properly connect all of the parts, yet any melting of the solder whatsoever will cause the connecting of the parts in such a way that it will be impossible for the cable to 35 work loose. If desired, the wedge after being driven in to spread the strands, may be withdrawn before the solder is melted, but the strands will stay spread out and will then be permanently held by the solder after 40 the latter is melted.

In Fig. 2, I have illustrated a slightly modified form in which the socket 10^a, instead of having a chamber of truncated conical form, has a chamber of substantially 45 cylindrical form, with an inwardly extending flange or shoulder 16 opposite to the end wall 12. The opening through this flange is substantially equal to the external diameter of the group of strands, while the main 50 body of the chamber is of greater diameter. Instead of placing a solder ring in engagement with the end wall 12, I place a solder sleeve 17 in engagement with the peripheral wall and the flange 16, and may make the 55 inner surface of the solder ring of conical form, so that the shape of the chamber, with the solder in place, will be substantially the same shape as the chamber shown in Fig. 1. Upon inserting the strands substantially into 60 engagement with the end wall 12, the wedge 14 may be driven into place to spread the strands out into engagement with the peripheral solder wall. By applying heat to the outside of the socket, the solder may be 65 melted to permanently connect the strands

to the peripheral wall and some of the solder may, and preferably does, run through the strands into engagement with the wedge. This construction possesses the advantage that the main body of the solder 70 is directly in engagement with the shoulder 16, and the slightest melting of the solder will bring some of it into engagement with the strands and hold the latter while the remainder of the solder abutting against the 75 shoulder will prevent the removal, or even the slightest loosening in case the solder does not properly adhere to said shoulder.

In Fig. 3, I have illustrated a socket 12^a possessing certain of the features shown 80 separately in Figs. 1 and 2. In this construction, there is not only the solder ring 15 across the ends of the strands, but the peripheral wall of the chamber is provided with a plurality of annular grooves 18, each 85 receiving and holding a solder ring 19, and each presenting a straight shoulder corresponding to the shoulder 16 of Fig. 2. It is, of course, evident that a greater or lesser 90 number of these solder rings may be employed, or that only a single ring may be used, of somewhat the same shape as is shown in Fig. 2. The solder of the ring 15 may flow lengthwise of the strands in the space therebetween and thus prevent the removal of the wedge, or if the wedge be withdrawn before the solder is melted and if the end wall be omitted, the solder itself may form the final end wall. The solder of the 95 peripheral rings 19 insure the proper connection of the strands to the socket and engage with the shoulders at the sides of the several annular grooves. It is of course evident that these grooves might have their end faces beveled inwardly to more effectively retain the solder or might be beveled outwardly to present an increased surface of the solder for engagement with the strands. 100

The three forms above described are adapted for use in connecting the end of a 110 cable to a bus-bar, generator, dynamo or other apparatus or machine, but it is evident that the invention is equally applicable for use in connecting together the ends of a plurality of cables. In making such connection, the attaching lugs of two or more 115 separate sockets, of the character shown in either Figs. 1, 2 or 3, could be directly bolted, or otherwise secured together, before or after being secured to the cable ends, or the 120 socket might be made with separate cable receiving openings in the same integral body.

In Fig. 4 I have shown a connector, including two annular sections 20 and 21, each having a chamber of truncated conical form 125 therein. The chambers will receive the cables at their outer or smaller ends, while the larger or base ends may be secured together in any suitable manner. As shown, the section 20 is threaded, while the section 130

21 presents a shoulder. A collar 22 is provided with screw-threads and a shoulder for engagement with the two sections for drawing them together and holding them with the abutting ends of the cables, spaced slightly apart or in direct engagement with each other. As shown, the peripheral surface of the chamber of each section is provided with a plurality of annular grooves 18, each containing a solder ring 19 similar to the rings shown in Fig. 3. Within the end of each cable is a wedge 23, the bases of the wedges coming opposite to each other when the parts are assembled. Instead of using two separate wedges, it is evident that a single, double-pointed wedge could be used, and be forced into the ends of the cables to spread apart the strands at the same time that the two sections 20 and 21 are drawn together by the threaded collar 22. It is also evident that instead of using the several annular solder rings, as shown in Fig. 4, each section might have a single ring, and the interior of the body of the socket 25 might be cylindrical as shown in Fig. 2. One or more separate solder rings might be inserted between the abutting ends of the two cables, and correspond in position and function to the solder ring 15, shown in Fig. 1.

In the various specific embodiments illustrated, I employ a single conical wedge and so design the socket as to facilitate or permit the driving of the wedge endwise between the strands in order to spread them apart. It is of course evident that instead of using a single conical wedge, a plurality of smaller wedges may be employed and driven in at different points in the ends of 40 the cable. Instead of having the wedge solid, it might be hollow so as to receive the central strand or strands only. As the main object of the wedge is to spread the strands apart into a space of greater transverse dimension than the entrance opening to the socket, it is of course evident that the spreading might be accomplished by a wedge member driven into the cable transversely thereof at the end or at a point 45 within the socket spaced a short distance from the end. Such a construction might or might not have an end wall, but would have an opening in the side to permit the entrance of the wedge. The solder which 50 would be incorporated in the socket as a part of the same article of manufacture, could be arranged in any of the various ways illustrated, or in any similar or equivalent way.

In all of the various forms of my invention, the wedge, after having performed its function of spreading apart the strands to a greater transverse dimension than the entrance opening to the socket, may be removed prior to the melting of the solder so 55 that the solder may either enter the space

formed by the wedge and upon cooling, form a permanent wedge, or it may bind together the strands in their spread condition and prevent the collapsing of the strands to a sufficient extent to permit the withdrawal 70 of the cable from the socket.

I have referred to the fusible material within the socket as being solder, but it is of course evident that the specific composition forms no portion of my present invention 75 and that various different metals or alloys may be employed as the solder, and the solder may even be a non-conductor of electricity, particularly where it is desired to secure the ends of cables other than electric 80 cables. To facilitate the proper adhesion of the solder and the socket wall, the latter may, if desired, be tinned.

It is also evident that a connector might be constructed similar to Fig. 2, but with the 85 end wall 12 omitted, or similar to Fig. 3, with the solder ring 15 omitted, without in any way departing from the spirit of the invention.

Having thus described my invention, 90 what I claim as new and desire to secure by Letters Patent is:

1. An article of manufacture for use as a connector for multiple strand cables, including a socket member having an entrance 95 opening adapted to receive the end of the cable and having a separate opening through which a wedge may be inserted to spread apart the strands of the cable, said socket having embodied therein a mass of solder 100 prior to the insertion of the cable or the wedge and said solder being fusible upon the application of heat to the exterior of the socket after the insertion of the cable and wedge. 105

2. A connector for electric cables, including a socket having a chamber therein including a portion of greater internal diameter than the entrance to said chamber, a mass of solder incorporated within said 110 chamber and of greater transverse dimension than said opening, and a wedge for forcing apart the strands of said cable and serving to prevent the escape of solder from said chamber upon the melting of the solder 115 by the application of heat to the exterior of the connector.

3. A connector for electric cables, including a socket having an end wall and a cable receiving opening opposite thereto, the 120 chamber being of greater diameter adjacent to said end wall than at said opening, and said end wall having an opening therein, a mass of solid solder received and retained within said chamber adjacent to said end 125 wall and encircling said second mentioned opening, and a wedge adapted to be forced through said second mentioned opening into the end of said cable to spread apart the strands of the latter, the solder being ca- 130

pable of being melted by the application of external heat to the connector after the insertion of the cable and wedge.

4. A connector for multiple strand cables, including a socket member having a chamber with openings at opposite ends thereof, one of said openings being adapted to receive the end of a cable, a mass of solder within said chamber and opposite to said opening and with which the end of the strands may engage, and a wedge adapted to be inserted through the other opening endwise into the cable between the strands thereof to spread said strands apart within the chamber, said solder being fusible upon the application of heat to the exterior of the socket after the insertion of the cable and wedge.

5. A connector for multiple strand cables, including a socket member having a chamber and an entrance opening adapted to receive the end of a cable, and a mass of solder within said chamber and opposite to said opening and with which the end of the strands may engage, said mass of solder having a central aperture therethrough to receive a wedge adapted to be driven endwise

into the cable to spread the strands of the latter apart within said chamber.

6. A connector for multiple strand electric cables including a socket having an interior chamber and openings at opposite ends thereof, one of said openings being adapted to receive the end of the cable and being of smaller cross sectional area than a portion of said chamber and the other of said openings being adapted to receive a wedge whereby the ends of the strands may be spread apart in said chamber to a diameter larger than said cable entrance opening, and a mass of solder incorporated within said chamber and of greater transverse dimension than said cable entrance opening, said solder being fusible upon the application of heat to the exterior of the socket after the insertion of the cable and wedge.

Signed at New York city in the county of New York and State of New York this 12th day of September A. D. 1914.
